US0D1109779S

(12) **United States Design Patent** (10) Patent No.: **US D1,109,779 S**
(45) Date of Patent: ** Jan. 20, 2026

(54) **EXCAVATOR**

- (71) Applicants: **Jiangsu Thintron Industrial Design and Research Institute Ltd.**, Jiangsu (CN); **Xuzhou XCMG Excavator Machinery Co., Ltd.**, Jiangsu (CN)
- (72) Inventors: **Jingyu Gao**, Jiangsu (CN); **Xuanyi Bian**, Jiangsu (CN); **Chaolei Hu**, Jiangsu (CN); **Zhiming Wang**, Jiangsu (CN); **Shuo Wang**, Jiangsu (CN); **Yaoyao Zhao**, Jiangsu (CN)
- (73) Assignees: **Jiangsu Thintron Industrial Design and Research Institute Ltd.**, Jiangsu (CN); **Xuzhou XCMG Excavator Machinery Co., Ltd.**, Jiangsu (CN)

(**) Term: **15 Years**

(21) Appl. No.: **29/993,363**

(22) Filed: **Mar. 13, 2025**

(30) **Foreign Application Priority Data**

Oct. 29, 2024 (CN) 202430682494.0

CLAIM

The ornamental design for an excavator as shown.

DESCRIPTION

FIG. 1 is a perspective view of an excavator showing our new design;

FIG. 2 is another perspective view thereof;

FIG. 3 is another perspective view thereof;

FIG. 4 is another perspective view thereof;

FIG. 5 is a front view thereof;

FIG. 6 is a rear view thereof;

FIG. 7 is an enlarged left side view thereof;

FIG. 8 is an enlarged right side view thereof; and,

FIG. 9 is a top view thereof.

1 Claim, 9 Drawing Sheets
